(57) CLAIM

The ornamental design for a desktop file organizer, as shown and described.

DESCRIPTION

FIG. 1 is a front perspective view of a desktop file organizer showing the new design;

FIG. 2 is left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The surfaces in broken lines in FIG. 6 are included for the purpose of showing portions that form no part of the claimed design.

1 Claim, 7 Drawing Sheets
